UNITED STATES PATENT OFFICE.

JOHN ROCKE, OF BLOOMINGTON, ILLINOIS.

AGITATOR FOR WASHING MACHINES.

Application filed May 26, 1926. Serial No. 111,692.

REISSUED

This invention relates to improvements in washing machines of the class employing driving means entering through the bottom of the container element and projecting upwardly therein to a point above the normal water line in said container, and wherein an agitator is designed to be supported and driven from said driving means from a connection above said normal water line.

10. The present invention is specifically directed to the structure and composition of an agitator fashioned to provide agitating means that operate at the bottom of the container for the purpose of inducing lateral deflection and upward projection of the fluid content.

15. The agitator herein is designed to be reciprocated about a vertical axis and has in view, because of structural characteristics, 20 the presentation of wide faced agitator blades, to the end of protecting clothes content within the container against damage and, incidentally, in connection with such service characteristic of said agitator blades, 25 of relative reinforcement and strengthening the same, and at the same time minimizing as to weight, by bridging relatively spaced agitator blades to provide a unitary hollow blade structure.

30. The invention also includes service utility because of the nature of the agitator structure as a whole being developed from substance material lighter than metal, as for instance, a phenolic condensation product, 35 whereby the shock attending reversing action of the agitator may be minimized to the smallest possible degree.

Referring to the drawings—

Fig. 1 is a perspective view of an agitator, 40 partly in broken section, and presenting diagrammatic showing of a container and a driving member for the agitator.

Referring more particularly to the drawings, 45 11 refers to a shaft adapted to be oscillating alternately in opposite directions. 12 is the disk portion of the agitator adapted, in practice, to be seated approximately at the bottom of the container, and 50 13 is a sleeve member integrally connected with said disk and extending upwardly therefrom for a substantial distance sufficient to be carried above the designed normal water line within the container. 14 is an 55 angularly fashioned portion at the interior upper end of the sleeve member, adapted for seating upon and in clutching relation

with a similar angularly fashioned portion 15 of drive shaft 11. 16 refers to relatively offset portions of a column 16^a to provide a bearing surface between said 60 column and sleeve portion 13 for service in centering said members respectively to prevent lateral shift of the lower portion of the agitator from impingement with the container content during operation. 65

Special reference is made to the agitator blades generally referred to as 17, the same being preferably formed integral with the body of the agitator and disposed at spaced intervals about the upper face of the disk, 70 said blades being formed from comparatively thin wall members 18, spaced apart, as shown, and united at their upper and outward face portions by a wall or bridge portion 19 thereby forming a narrow channelway between the blade sections that serves for strengthening as well as reducing the weight of the agitator as a unit, and in addition serves to present a wide abrasive surface that will not tear or damage the clothes 80 in the container when the agitator is reciprocated.

In practice, reverse action attending the operation of agitators, when such agitators are formed from metal or absorbent material, as wood, has resulted in excessive jar and attendant strain, in case of metal, because of its natural specific gravity, and in case of wood, because when soaked with water, it becomes very heavy. This jar and 90 attendant strain has caused wearing action upon the machine parts and unnecessary power requirement.

The present invention contemplates the formation of the agitator from a phenolic 95 condensation product. The use of such a material in the agitator affords many important advantages which have not been obtainable heretofore in the washing machine art through the use of wood or metal. The 100 agitator is impervious to water, is much lighter than metal, and is far more serviceable. It does not corrode, and even after a long period of service, the active surfaces remain smooth and unbroken. After use, 105 a metallic dolly becomes corroded and covered with a small scale which results from the action of the soaps and alkalies used in the washing operation. Such a roughened dolly has a disastrous effect upon clothes, especially 110 if they are of fragile and soft material. A dolly formed from the material indicated by

the present invention retains its original smoothness throughout its life, and in addition does not warp or bend. Owing to its light weight, the operation of the machine is 5 rendered less expensive due to the fact that less power is consumed in reciprocating the dolly.

The applicant's dolly is more sanitary than the previously known metallic and 10 wooden dollies, as it does not develop permanent accumulations of deleterious matters such as dirt, grease and the like. It has proven to be more efficient due to the resulting increases of water agitation. This is 15 probably due to the fact that a dolly formed of a phenolic condensation product has less skin friction than the usual metallic dollies.

A further advantage of the applicant's dolly is that much of the noise incident to 20 the operation of former washing machines of this type is eliminated by its use.

Still another very important advantage is that the applicant's dolly is a non-absorber and non-conductor of heat. This has the advantage that the bearings on which the dolly 25 is mounted are shielded from the heat of the washing fluid or water, and that the dolly itself may be readily removed immediately after the termination of the washing operation if desired.

The above description, it is thought, fully presents the material features of advantage of the agitator herein, and presents a pref-

erable form of embodiment. However, other characteristics of service and advantage are 35 obviously included within the agitator structure, and with respect to the form presented, it is similarly obvious that other forms may be employed that may serve measurably to perform the full functions of 40 that of the disclosure, and hence all structures and forms of structures possessing the utilities herein presented are claimed as being within the concept of invention herein set forth. 45

What I claim is:

1. An agitator adapted for use within a washing machine tub formed from a phenolic condensation product.
2. An agitator adapted for use within a 50 washing machine tub comprising a member having a plurality of baffles thereon, said member and baffles being formed from a phenolic condensation product.
3. A dolly for washing machines comprising a disk, a hollow sleeve member projecting upwardly from the center portion of said disk, a plurality of spaced baffle members provided upon the upper portion of said disk and adjacent the lower end of 60 the sleeve member, the said disk, sleeve member, and baffles being integrally formed from a phenolic condensation product. 65

In testimony whereof I have hereunto affixed my signature.

JOHN ROCKE.
